UNITED STATES PATENT OFFICE.

WILLIAM A. HAYES, OF PHILADELPHIA, PENNSYLVANIA.

PACKAGE-TIE.

No. 895,015.

Specification of Letters Patent.

Patented Aug. 4, 1908.

Application filed October 24, 1907. Serial No. 399,072.

To all whom it may concern:

Be it known that I, WILLIAM A. HAYES, a citizen of the United States, residing at Philadelphia, in the county of Philadelphia and State of Pennsylvania, have invented 5 certain new and useful Improvements in Package-Ties, of which the following is a specification.

The purpose of the present invention is to 10 provide a novel fastening means for securing bundles of papers or the like.

The invention contemplates a package-tie which can be employed with equal facility in connection with various sizes of bundles and 15 which is peculiarly designed so as to be easily and quickly applied to the bundle or removed therefrom.

A further object is the provision of a package tie which can be used repeatedly without 20 any appreciable wear upon the fastening device and with very little wear upon the binding cord attached thereto.

For a full description of the invention and the merits thereof and also to acquire a 25 knowledge of the details of construction and the means for effecting the result, reference is to be had to the following description and accompanying drawings, in which:

Figure 1 is a plan view of a package having 30 the improved tie applied thereto. Fig. 2 is a similar view showing the manner of securing the binding cord when the same has an excessive length. Fig. 3 is a transverse sectional view through the tie member. Fig. 4 35 is a longitudinal sectional view through the same. Fig. 5 is a detail perspective view of the tie member. Fig. 6 is a rear view of the package.

Corresponding and like parts are referred 40 to in the following description and indicated in all the views of the drawings by the same reference characters.

The package tie may be formed of any 45 suitable material such as wood, glass, metal or the like, although metal is preferably employed owing to the fact that it is more durable than other materials.

The numeral 1 designates the base which 50 is provided adjacent one of its edges with an opening 2 designed to receive a flexible binding member such as the cord 3, one end of the latter being knotted to prevent it from pulling through the opening. In the preferred form of the invention the edges of this

opening 2 are pressed outwardly and reinforced so as to prevent injury to the cord and cause the tension in the cord to hold the base firmly against the package. Rigid with the base 1 is a binding head 4, a notch 5 being formed between the binding head and the base and extending along one of the longitudinal edges of the former. This notch is V shaped so as to have a wedge like action upon the binding cord and the mouth of the said notch faces that side of the base 1 formed with the opening 2 through which the binding cord is inserted. A longitudinal groove 6 is formed in the outer face of the binding head 4, the sides of the groove being curved outwardly and the said groove gradually becoming deeper toward the ends thereof which terminate in notches 7 which communicate with the before mentioned longitudinally disposed notch 5. The opposite sides of the binding head 4 are beveled as 75 indicated at 8 and the portions of the binding head upon opposite sides of the groove 6 are provided with corresponding depressions 9 and 10 arranged transversely with respect to the groove, the latter mentioned depression flaring outwardly toward the groove 6 and gradually becoming deeper as it approaches the same.

In the application of the package tie the base 1 is placed against one of the faces of 85 the package at substantially the central portion thereof and the flexible cord 3 drawn around one of the edges of the package to a point upon the central portion at the back of the package. The said binding cord is 90 then turned at right angles as indicated at 11 and wound entirely about the package, the loop thus formed passing through the longitudinal notch 5 between the base and binding head. After forming this loop the 95 cord is passed around that portion of the same at the back of the package as indicated at 12 and then wound about the package to complete the loop first started, the end of the cord being drawn around the 100 binding head so as to enter the longitudinal notch 5. After this operation the cord is drawn through the groove 6, being thereby placed in engagement with one of the notches 7 and looped under that portion of the cord at the opposite end of the longitudinal notch 5. A sharp pull then tends to draw the cord upwardly within the groove 6

and the depression 10. If found desirable the end of the cord may then be looped several times about the body portion of the cord in order to render the tie more secure, as 5 shown at 13^a.

Should the cord be excessively long for the bundle being operated upon the end of the cord is wound a number of times about the bundle after being secured as previously described, the various loops thus formed being received within the depressions 9 and 10. After the excessive length has thus been taken up the end portion of the binding cord is passed transversely across the several 15 loops as indicated at 13, and drawn around the two notches 7 so as to extend across the loops of the cord and pull the same inwardly as indicated at 14, and is then looped several times around the body portion of the cord 20 as at 15. It will thus be apparent that the tie can be quickly applied to a package or removed therefrom and the various members constituting the package held securely together.

25 Having thus described the invention, what is claimed as new is:

1. In a package tie, the combination of a base, a binding head projecting from the base and having a groove formed therein, 30 the said binding head being also provided with a depression arranged transversely with respect to the groove, and a binding cord carried by the base and adapted to have an interlocking connection with the binding head.

2. In a package tie, the combination of a base, a binding head projecting from the base and having a groove formed therein, a notch being formed between the base and 40 the head and a depression being formed in the head in communication with the groove and arranged transversely with respect thereto, and a binding cord carried by the

base and adapted to have an interlocking connection with the head. 45

3. In a package tie, the combination of a base, a head carried by the base, a notch being formed between the base and the head and opposite sides of the head being provided with notches communicating with the 50 first mentioned notch, a longitudinal groove being formed in the head connecting the second mentioned notches, and a flexible binding member carried by the base and adapted to have an interlocking connection 55 with the notched and grooved portions of the binding head.

4. In a package tie, the combination of a base, a binding head carried by the base, a longitudinal notch being formed at the base 60 of the binding head and the said binding head being provided upon opposite sides with notches communicating with the before mentioned longitudinal notch, a groove being formed in the head connecting the 65 second mentioned notches, and depressions being formed upon opposite sides of the groove, and a flexible binding member carried by the base and adapted to have an interlocking connection with the notched and 70 grooved portions of the binding head.

5. In a package tie, the combination of a base, a binding head projecting from the base and having a groove formed in the outer portion thereof, a notch being located 75 between the base and the head and arranged approximately parallel with the groove, and a binding cord carried by the base and adapted to have an interlocking connection with the binding head.

In testimony whereof I affix my signature in presence of two witnesses.

WILLIAM A. HAYES. [L. S.]
